UNITED STATES PATENT OFFICE.

JAMES M. MILLER, OF WASHINGTON, DISTRICT OF COLUMBIA.

AIRPLANE.

Application filed July 9, 1927. Serial No. 204,610.

This invention relates to airplanes and has particular reference to the provision of wing supporting struts which will serve the double use of supporting struts as well as 5 serving as ailerons.

An object of the invention is to provide in an airplane a more prompt lifting of the plane from the ground or runway in its take-off in ascending and better control in making 10 landings, thereby avoiding excessive taxiing.

Another object is to provide an aileron strut support for the wings of sufficient strength and width at its wider end where it 15 is attached to the fuselage of the airplane and which decreases in width as it approaches its proper point of attachment to the wing.

A further object of this invention is to 20 provide an aileron which is located in the direct line rearwardly and in the air slip stream from the propeller, whereby it will receive the benefit of its lifting power and apply it at the point of greatest weight.

Another object is to provide an improved 25 means of control of the angles of incidence of these aileron struts as desired and maintain such angle by the use of suitable means the control of which is located within the 30 fuselage.

Further objects and advantages of this 35 invention will be apparent from the following description, reference being had to the accompanying drawings wherein preferred embodiments of this invention are clearly shown and wherein,—

Figure 1 is a side quarter view of a monoplane having struts designed according to this invention;

Fig. 2 shows a biplane provided with a 40 similar form of strut;

Figs. 3 and 4 show detailed views of two forms of struts;

Fig. 5 is a front view of a monoplane 45 showing the arrangement of aileron struts in the slip stream of the propeller; and

Fig. 6 shows a side quarter view of a monoplane of a modified form wherein the supporting struts are arranged above the wings.

Referring to the drawings, in the several 50 views numeral 1 indicates the fuselage of an airplane which is provided with the usual running and landing gear wheels 2, propeller 3, and rear steering and stabilizing controls 4 and 5, and tail skid 6. In Fig. 1, a monoplane is shown as having wings 7. Located

on each side of the airplane and extending upwardly and outwardly from the fuselage to the underside of each plane wing, is shown a pair of aileron struts 8 which constitutes 60 the novel feature of this invention. Each of said struts comprises a relatively wide portion located closely adjacent the fuselage and pivoted thereto in any desired manner for example as shown more clearly in Fig. 65 4 by a ball and socket joint 9, one member of which 9' is attached to the side of the fuselage. Said strut is shown as gradually diminishing in width from its lower end upwardly to the upper end where it is attached to the underside of the wing by a similar ball and socket joint 10, one member of which 10' is attached to the wing.

A means for controlling and maintaining 75 the angles of incidence of the struts 8 is shown which may comprise an outwardly extending lug 11 on each strut which is pivoted to a link 12. A lever 13 preferably located within the fuselage is pivoted to the link 12 and serves to move the struts to any desired 80 position.

Fig. 3 shows a modification wherein an aileron 8' is mounted to rotate around a rigid strut 16 which is attached to the wing 85 and fuselage respectively by means of fittings 14, 14' while a lug or extension 11' is provided for engagement pivotally with operating links 12.

Fig. 2 shows how the invention may be 90 applied to a biplane having wings 17, 18. An aileron strut 19 similar to the strut 8 in Fig. 1 is pivotally mounted at its wide end to the fuselage and at its upper end to the wing. A modified form of operating means 95 is shown which may take the form of a circular rack segment 20 mounted on the strut and operatively engaged with a corresponding segment and lever 21.

Particular attention is directed to Fig. 5 which clearly shows an important feature of 100 this invention. In order to obtain a maximum lifting and controlling effect from the aileron struts and apply the same at the point of maximum weight of the airplane, the struts have been located so that the wider 105 portions thereof are positioned directly in and rearwardly of the air slip stream flow from the propeller.

Fig. 6 shows a further modification where- 110 in a monoplane having wings 22 is provided with a pair of aileron lifting struts built according to this invention. Numeral 23

indicates one of these struts pivotally mounted as at 24 and 25 to the fuselage and wing respectively. The control for struts 23 may be of the form shown in Fig. 1 or Fig. 2.

- 5 In operation, when the airplane is in the act of taking off for an ascent, the aileron struts are set to give a maximum lifting effect. It is well known that a low ground speed does not provide the necessary lift for a 10 quick take-off. The provision of aileron lifting struts positioned as shown and described directly in rear of the propeller in the high velocity air slip stream therefrom, will obviously add an enormous lifting effect to 15 supplement the relatively low lifting effect derived from the main wings of the airplane. As a result, a quick take-off at lower speeds than usual may be obtained thereby eliminating the necessity of the usual long 20 runways. While in flight, the aileron struts may be operated in opposite directions to assist in banking on turns. During the act of landing, the enhanced lift obtained from

the air slip stream from the propeller the aileron struts will enable the airplane to 25 land at a speed lower than usual.

I claim:—

In an airplane, a fuselage provided with rigid wing surfaces and a propeller, struts extending from said fuselage at an angle to 30 said wing surfaces, ailerons pivotally mounted on said struts, said ailerons having a maximum width immediately adjacent the fuselage and tapering uniformly to said wing surfaces, that portion of maximum 35 width of said ailerons being located in the air slip stream from said propeller for providing a lifting effect by impact from said stream on its underside and a braking effect by impact from said stream upon its upper 40 side at negative angles of incidence, and means for varying the angles of incidence of said ailerons between positive and negative angles of incidence.

In testimony whereof I affix my signature.
JAMES M. MILLER.
